UNITED STATES PATENT OFFICE.

EPHRAIM MUSSelman, OF CELINA, OHIO.

DESIGN FOR A NECKTIE-HOLDER.

SPECIFICATION forming part of Design No. 32,985, dated July 24, 1900.

Application filed March 17, 1900. Serial No. 9,119. Term of patent 14 years.

To all whom it may concern:

Be it known that I, EPHRAIM MUSSelman, a citizen of the United States, residing at Celina, in the county of Mercer and State of Ohio, have invented and produced a new and original Design for a Necktie-Holder, of which the following is a specification.

This invention relates to a new and original design for a necktie-holder; and it has for its object to provide a design of this character which shall be both useful and ornamental.

The leading feature of the design resides in a folded body having a U-shaped clip portion provided with side members arranged in substantial parallelism, one of which side members is of a rectangular shape and flat throughout with straight side edges and the other of which members is shorter than the flat member and bowed inwardly toward the same, said body being further provided with a narrow downturned prong curving into one end of the longer flat side member beyond the contiguous terminal of the shorter side member and lying opposite one face of said longer flat member centrally between the straight edges thereof, the said prong being shorter in length and materially narrower than the longer flat side member and having a longitudinal curvature from end to end.

In the drawings, Figure 1 is a perspective view of a necktie-holder embodying the herein-described design viewing the holder from one side thereof. Fig. 2 is a similar view of the holder viewing it from the opposite side. Fig. 3 is an elevation of the prong-bearing

side of the body. Fig. 4 is a sectional view on the line 4 4 of Fig. 3.

Referring particularly to the drawings, the numeral 1 designates the body of the holder, which is of a folded form and provided with the two side members 2 and 3. The two side members 2 and 3 of the body are arranged in substantial parallelism and are of different lengths, the longer of said members 2 being of a rectangular shape and flat throughout with straight side edges and the other side member being provided with a rounded terminal 4 and bowed inwardly toward the longer flat member. The said folded body 1 is also provided with a narrow downturned prong 5, curving into one end of the longer flat side member 2 and arranged opposite one face thereof centrally between the straight side edges of the same. The said downturned prong 5 is shorter in length and materially narrower than the adjacent flat member 2 and tapers in width to a point. The prong 5 is also longitudinally curved from end to end and bowed inwardly toward the adjacent side member 2.

What is claimed is—

The design for a necktie-holder herein shown and described.

In testimony that I claim the foregoing as my own I have hereto affixed my signature in the presence of two witnesses.

EPHRAIM MUSSelman.
